TEXTILE FABRIC OR SIMILAR ARTICLE

Harry Odzer, New York, N. Y.

Application October 22, 1952, Serial No. 21,934

Term of patent 3½ years

(Cl. D92—1)

To all whom it may concern:

Be it known that I, Harry Odzer, a citizen of the United States of America, residing in New York city, county of New York, and State of New York, have invented a new, original, and ornamental Design for a Textile Fabric or Similar Article, of which the following is a specification, reference being had to the accompanying drawing, forming part thereof.

Fig. 1 is a plan view of a textile fabric or similar article, showing my new design.

Fig. 2 is an edge view thereof.

The design unit is outlined by broken lines and is repeated as indicated.

I claim:

The ornamental design for a textile fabric or similar article, substantially as shown and described.

HARRY ODZER.
